WITNESS:

William L. Walker
INVENTOR
BY *Victor J. Evans*

ATTORNEY

Patented Dec. 16, 1924.

UNITED STATES PATENT OFFICE.

WILLIAM L. WALKER, OF SOUTH PORTLAND, MAINE.

BILL FILE.

Application filed April 7, 1924. Serial No. 704,849.

To all whom it may concern:

Be it known that I, WILLIAM L. WALKER, a citizen of the United States, residing at South Portland, in the county of Cumberland and State of Maine, have invented new and useful Improvements in Bill Files, of which the following is a specification.

The object of this invention is the production of a bill file in which bills or similar documents are firmly clamped on a rigid support that forms the upper and inclined plate of a bent spring body, and which, upon compression toward the base thereof will automatically release the clamping means, so that bills may be readily inserted in or removed from the device.

With the above broadly stated object in view and others which will appear as the nature of the invention is better understood, reference is to be had to the drawing which accompanies and which forms part of this application.

In the drawing:—

Figure 1 is a plan view of the improvement.

Figure 2 is a rear end view thereof.

Figure 3 is a side elevation thereof.

Figure 4 is an approximately central longitudinal sectional view through the improvement showing bills clamped thereon.

Figure 5 is a fragmentary edge view showing the upper bill supporting element of the spring body compressed against the base thereof to swing the clamp to bill releasing position.

As disclosed by the drawing I make use of a sheet of comparatively thin spring metal. This sheet is rounded upon itself, as at 1, to provide a flat base 2 and a top or table 3 which is arranged at an upward inclination with respect to the base. To reinforce the base and the table I bend or flange the edges thereof, as indicated by the numeral 4. The free end of the table 2 is also provided with an angular downwardly directed flange 5. The base is of a greater length than the table and at suitable points adjacent to its ends the same is depressed to form outwardly projecting feet 6. The feet also add to the rigidity of the structure.

The base 2, adjacent to its free end is preferably slotted and the metal bounded by the slit rounded to provide spaced eyes 7. These

eyes receive therethrough the straight ends 8 of the bill clamping element. The bill clamping element is constructed of a single strand of wire or other resilient material, having angle arms 9 arising from its ends 8 that pass through suitable openings in the flange 5. The wire strands are rounded in the same direction from the angle arms 8 and are connected. This last mentioned portion forms the substantially U-shaped gripping element of the clamp and is designated in the drawings by the numeral 10. Because of the tendency of the table 3 to spring away from the base 2 the gripping element 10 of the clamp will be forced into tight engagement with the table so that bills may be effectively gripped between the said clamping element and the table. A downward pressure on the table will cause the angle arms 9 of the gripping element to ride through the openings 11 in the flange or ledge 5 of the table, and consequently swing the gripping element to the position illustrated in Figure 5 of the drawings, so that bills may be readily arranged on or removed from the table.

Having described the invention, I claim:—

1. A bill holder including a metal plate rounded upon itself to provide a base and a table arranged angularly of and designed to spring away from the base, a wire gripping element including a central U-shaped portion having angle legs passing through openings in the free end of the table, and said legs having offset ends which are journaled in bearings in the base.

2. A bill holder, comprising a resilient metal plate bent upon itself to provide a base and a table which is swingable away from the base, said base and table having their edges formed with reinforcing flanges, and the outer end of the table being flanged downwardly and provided with openings, a bill gripping element constructed of wire to include a U-shaped portion having angle arms depending from the ends thereof and passing through the openings in the flange of the table, and said arms having outturned ends which are journaled in bearings in the base.

In testimony whereof I affix my signature.

WILLIAM L. WALKER.
